INVENTOR

Jacob C. Moler

BY

W. J. Davis, Lawyer
ATTORNEY

UNITED STATES PATENT OFFICE.

JACOB C. MOLER, OF MULBERRY, KANSAS.

COAL-DRILL-SOCKET-RETAINING APPARATUS.

1,253,511.

Specification of Letters Patent. Patented Jan. 15, 1918.

Application filed December 7, 1916. Serial No. 125,805.

To all whom it may concern:
Be it known that I, JACOB C. MOLER, a citizen of the United States, residing at Mulberry, in the county of Crawford and State 5 of Kansas, have invented certain new and useful Improvements in Coal-Drill-Socket-Retaining Apparatus, of which the following is a full, clear, and exact description, such as will enable others skilled in the art 10 to which it appertains to make and use the same.

The invention relates to a retaining device for locking the drill socket of coal drills to the thread bar of the drilling machine 15 so that the socket is securely held in operative position on the thread bar when in operation and can be easily and quickly removed when desired.

The drill socket is frequently removed 20 from the thread bar and replaced thereon for the purpose of changing drills, grinding the drills and other reasons and it is essential that an easily and quickly attachable and detachable means be provided so 25 that no time will be lost in changing the drills, it being of still further advantage to be able to attach or detach the drills without the aid of other tools, such as punches, wrenches and the like as it is not convenient or expeditious for the workman to always have such tools present when the drill 30 is to be changed.

The present invention seeks to provide an improved retainer for detachably attaching drill sockets to the thread bar of coal drilling machines so that the socket can be instantly attached to or detached from the thread bar without the aid of other tools.

With these and other objects in view the 40 invention consists in the features of construction, combinations and arrangements of parts hereinafter set forth and more fully pointed out in the appended claims, the accompanying drawings illustrating an application of the invention to the drill socket and thread bar of a coal drilling machine.

In the drawings:—

Figure 1 is a view in elevation of a coal drill socket with the improved retainer shown in 50 dotted lines and fragmentary views of the thread bar and a coal drill.

Fig. 2 is a view in elevation of the socket and fragmentary views of the coal drill and thread bar.

Fig. 3 is a sectional view taken on line 5-5 2-2 of Fig. 2.

Fig. 4 is a fragmentary view in elevation of the thread bar.

The thread bar 5 is of common and well known construction in the art pertaining to coal drilling machines, excepting the slot 6 in which the retainer 7 is mounted on the pin 8.

The coal drill 9 and the socket 10 are of common and well known construction, excepting that the rectangular hole 11 is so positioned and arranged as to cooperate with the retainer 7 in retaining the socket 10 on the thread bar 5.

The slot 6 is provided in the thread bar 7 5, in which is pivoted on the pin 8 the retainer 7, the latter being provided with lug 12 to engage the end 13 of the hole 11 while the end 14 of the retainer is larger and heavier than the end thereof from which the lug 12 projects, the bulk and weight of the end 14 being positioned on the opposite side of the pin 8 from the lug 12.

The retainer being constructed and positioned in the foregoing manner causes the end 14 thereof to over balance the opposite end and always hang in the position shown in Fig. 3 when the thread bar is in an upright position as it usually is, and this weight of the end 14 of the retainer also is acted upon by centrifugal force when the thread bar is revolving, as it always is while in operation, the centrifugal force acting and producing this result when the thread bar is in horizontal position as shown, it being understood that the thread bar is operated in horizontal as well as in vertical position.

From the foregoing it will be understood that the retainer 7 will always securely retain the socket 10 on the thread bar, whether the latter be in vertical or horizontal position, and that the revolving of the thread bar due to the operation thereof will produce centrifugal force in the end 14 of the retainer and aid in retaining the socket on the bar.

The socket 10 is not usually a tight fit on the thread bar when the wall 15 of the socket bears against the end 16 of the thread bar, thus allowing sufficient movement of the socket in the direction of the thread bar to withdraw the lip 17 of the lug 12 from

the hole 11 so that the socket is easily and instantly removed from the thread bar when it is desired to remove it.

The socket retainer is of particular advantage for the retaining of drill sockets on the thread bar of coal drills and will save considerable time in the changing of drills, the retainer being instantly operable and always dependable both in attaching and detaching the socket to the thread bar.

What I claim as new, and desire to secure by Letters Patent, is:—

1. In drill socket retaining apparatus for coal drills, a thread bar, a retainer pivoted within said thread bar, a retaining lug

on said retainer and projecting from said thread bar, and a lip on said lug to lock a drill socket on said thread bar.

2. In drill socket retaining apparatus for coal drills, a thread bar, a retainer extending longitudinally of said thread bar and pivoted therein, a retaining lug on one end of said retainer and projecting from said thread bar, the opposite end of said retainer being heavier than the end provided with said lug, and said heavier end of said retainer inclining to the side of said thread bar opposite said retaining lug.

JACOB C. MOLER.
